Arnold V. Weiss, 20438 Septo St., Chatsworth, Calif.,
and Bernhardt B. Weiss, 6427 W. 82nd St., Los Angeles,
Calif.

Filed July 6, 1965, Ser. No. 86,034

Term of patent 14 years

(Cl. D52—6)

FIG. 1 is a side elevational view of a pendulum-actuated scribe for Lissajous-like curves, showing my new design;

FIG. 2 is a top plan view thereof;

FIG. 3 is a fragmentary view on an enlarged scale, looking downwardly on arrows III—III of FIG. 1;

FIGS. 4 and 5 are front and rear elevational views respectively; and

FIG. 6 is a sectional view on an enlarged scale looking downwardly on arrows VI—VI of FIG. 1.

The paper and the retaining clips shown in broken lines in FIGS. 1, 2, 4 and 5 are depicted for illustrative purposes only.

We claim:

The ornamental design for a pendulum-actuated scribe for Lissajous-like curves or the like, substantially as shown and described.
